UNITED STATES PATENT OFFICE.

THOMAS LANGHAM, OF PHILADELPHIA, PENNSYLVANIA, ASSIGNOR TO
THOMAS DOLAN, OF SAME PLACE.

DESIGN FOR A BORDER FOR KNIT FABRICS.

Specification forming part of Design No. 5,474, dated January 16, 1872.

Specification describing a new and original Design for a Border for Knitted Fabrics, invented by THOMAS LANGHAM, of Philadelphia, Pennsylvania.

The nature of my design is fully represented in the accompanying photographic illustration, to which reference is made, and which shows a portion of an ornamental border for knitted fabrics, the said border being either separate from or forming part of the fabric.

The border, which is scalloped at the outer edge, consists of a series of parallel ribs united

by loops in a manner too clearly illustrated in the photograph to need minute explanation.

What I claim as my invention is—

The design for a border for knitted fabrics, substantially as shown and described.

In testimony whereof I have signed my name to this specification in the presence of two subscribing witnesses.

THOMAS LANGHAM.
